UNITED STATES PATENT OFFICE

146,799

DESIGN FOR A HELICOPTER

Agnew E. Larsen, Jenkintown, Pa., assignor, by
mesne assignments, to The Glenn L. Martin
Company, Baltimore, Md., a corporation of
Maryland

Application May 16, 1945, Serial No. 119,561

Term of patent 14 years

(Cl. D71—1)

To all whom it may concern:

Be it known that I, Andrew E. Larsen, a citizen of the United States and resident of Jenkintown, in the county of Montgomery and State of Pennsylvania, have invented a new, original, and ornamental Design for a Helicopter, of which the following is a specification, reference being had to the accompanying drawings, forming part hereof, in which

Figure 1 is a side perspective view of a helicopter, showing my new design as it appears with the landing gear retracted.

Figure 2 is a top perspective view with the landing gear in extended position.

The curvature of the underneath portion of the empennage is substantially uniform throughout.

I claim:

The ornamental design for a helicopter, substantially as shown and described.

AGNEW E. LARSEN.
